UNITED STATES PATENT OFFICE.

ARCHILLES A. BARTON, OF GLENDALE, CALIFORNIA.

BUCKET FOR DEEP-WELL PUMPS.

1,367,451.

Specification of Letters Patent.

Patented Feb. 1, 1921.

Application filed September 23, 1918. Serial No. 255,385.

To all whom it may concern:

Be it known that I, ARCHILLES A. BARTON, a citizen of the United States, residing at Glendale, in the county of Los Angeles and 5 State of California, have invented a new and useful Improved Bucket for Deep-Well Pumps, of which the following is a specification.

My invention relates to the art of pumping, and more particularly to the construction of pumps which are adapted to lift fluids from considerable depths, these pumps being known in the art as deep well pumps.

15 In such pumps it is standard practice at the present time to provide a bucket having inner and outer seats on which a clapper is seated this clapper sliding freely on a valve stem or rod. One variation of such a bucket 20 is shown in the patent to S. M. Fulton, 1,164,178, patented December 14, 1915. In such a bucket the inner seat is necessary as the clapper must be loose enough to slide 25 freely on the valve stem and if made a loose fit water will pass downwardly between the clapper and the stem unless this is prevented by an inner seat. This passage of water occurs whenever the inner 30 seat starts to leak with the result that the stem and clapper are rapidly eroded. The standard forms of bucket and valve as used in deep well pumps therefore give considerable trouble and very rapidly become inefficient.

35 The principal object of my invention is to provide an improved form of valve clapper for use in such a pump.

Further objects and advantages will be made evident hereinafter.

40 Referring to the drawings, which are for illustrative purposes only,

Figure 1 is a side elevation, partly in section, through a device showing one embodiment of my invention.

45 Fig. 2 is an enlarged view of the preferred form of valve.

Fig. 3 is a cross-section on line 3—3 of Fig. 1, being viewed in the direction of the arrow.

50 Fig. 4 is a cross-section on line 4—4 of Fig. 1, viewed in the direction of the arrow.

In the form of my invention illustrated in these drawings, a pump barrel 11 is shown in which is placed an upper bucket 55 12 and a lower bucket 13. Each of the

buckets consists of a spider 14 having a central hub 15. Formed on the exterior of each of the spiders 14 is a cylindrical machined surface 16 on which cylindrical spacing rings 17 slide. Cuppleathers 18 are 60 placed between the spacing rings 17, the lower cuppleather pressing against a flange 19 formed on the spider 14 and the upper spacing ring being forced downwardly by a nut 20 threaded on the spider 14. 65

Secured in the upper portion of the bucket 12 is a seat 21 which is preferably formed of bronze or the like, this seat being secured in place by a threaded set screw 22. Turned to make a liquid tight contact with 70 the seat 21 is a valve or clapper 25, this clapper having a central cavity 26 in which a series of cuppleathers 27 is placed. The cuppleathers 27 are held apart by spacing rings 28 and are locked in place by a gland nut 75 29, the lower cuppleather 27 pressing against a shoulder 30 formed on the clapper 25. A conical, helical spring 31 presses against the top of the clapper 25, and in the case of the lower valve presses against a collar 32 in 80 which is secured a solid socket stem 33. This stem has a turned shoulder 34 on which the hub 15 of the lower bucket is pressed, this shoulder terminating in a head 35 at the lower end and in a threaded extension 36 85 at the upper end on which a retaining nut 37 is threaded.

Secured in the upper end of the collar 32 is a pump rod 38, this pump rod passing through a hollow bucket stem 39 which is 90 provided with a turned shoulder 40 on which the hub 15 of the upper bucket is pressed. The turned shoulder 40 terminates in a head 41 at one end and in a threaded extension 42 at the other on which a nut 43 is 95 threaded. The spring 31 of the upper bucket presses against a collar 44 threaded on the outer end of the hollow bucket stem 39, this collar also having an outer pump rod 45 secured in the upper end thereof. 100

The method of operation of the invention is more or less obvious. The rods 38 and 45 are reciprocated alternately by means of a suitable pump head, water being supplied to the bottom of the pump barrel 11 and moved 105 upwardly by each valve in turn. On the downward stroke of either bucket the clapper 25 of that bucket is lifted against the tension of the spring 31 and water flows between the clapper and the seat 21. On the 110

upstroke the clapper 25 seats solidly and lifts the water. The form of construction shown is similar to the standard type of bucket now employed, but has certain novel features which will now be pointed out.

In the first place, the clapper 25 makes a water tight closure at only one point, namely, against the seat 21. This is made possible by the use of the cuppleathers 27 which make 10 a tight closure between the clappers 25 and the sleeve 39 on one hand and the rod 33 on the other. These cuppleathers are so placed, as will be seen from the drawing, that they are forced tight by water pressure from 15 above and are relieved by water pressure from below. As a result of the bucket arrangement of the cuppleathers, the clapper, when the bucket is lifting, forms a very tight closure and whenever the bucket is 20 dropping the clapper readily lifts due to the release of the pressure on the cuppleathers 27.

It will be noted that the cup leathers 27 form a water tight but flexible joint between the clapper 25 and the rod 33. Certain new 25 and useful results are produced by this construction which may be enumerated as follows:

a. Only one seat for the clapper is necessary, the inner seat commonly found on deep 30 well pumps being omitted. This inner seat, which in standard pumps is necessarily of small area as compared to the outer seat, is always the first to leak and by its omission one fruitful source of trouble is eliminated. 35 As the travel of the clapper on the rod 33 is small the cup leathers 27 wear very little and need not be renewed for long periods.

b. In the event that the outer seat is not 40 truly concentric, or not located in a plane truly perpendicular, to the rod 33 the closure of the clapper on the valve seat is nevertheless perfect as the cup leathers will yield sufficiently to allow the clapper to seat.

c. The absolutely tight closure of the cup 45 leathers 27 on the rod 33 prevents leakage along the rod and prevents this rod from being cut away by such leakage.

d. As the cup leathers 27 fit tightly around 50 the rod 33 they positively guide the clapper causing it to seat evenly all around without gaging the seat. Where a loose two seated clapper is used the edge thereof catches in the seat and tends to gage or chip away the metal.

e. The soft cup leathers fitting tightly 55 around the rod tend to prevent sand or gravel from getting into the space between the cup leathers and the rod and thus prevent the clapper from being jammed open 0 as often occurs with a two seated clapper fitting loosely around its rod.

A further novel feature of my invention is

the use of the conical helical spring 33 arranged as shown.

A still further novel arrangement is the 65 insert seat 21, the peculiar method of securing the buckets on the rod 34 and the sleeve 39, and the method of securing the cuppleathers 18 on the exterior of the barrel.

While I have particularly described my 70 invention as used in deep well pumps it is understood that I do not limit my invention to the form shown but the same may be used in various forms of pumps in which a valve or clapper is used on buckets.

What I claim is:—

1. A bucket structure for use in deep well pumps comprising a cylindrical bucket; a seat formed on the top of said bucket about an opening extending therethrough; a 80 bucket stem extending through said opening, the entire weight of said bucket being carried by said stem; a clapper sliding on said stem, said clapper seating in fluid tight relationship on said seat; and flexible means 85 for making a fluid tight joint between said clapper and said stem.

2. A bucket structure for use in deep well pumps comprising a cylindrical bucket; a seat formed in said bucket about an opening 90 extending therethrough; a bucket stem extending through said opening, the entire weight of said bucket being carried by said stem, a clapper sliding on said stem, said clapper seating in fluid tight relationship on 95 said seat; and flexible packing in said clapper about said stem.

3. A bucket structure for use in deep well pumps comprising a cylindrical bucket; a seat formed on the top of said bucket about 100 an opening extending therethrough; a bucket stem extending through said opening, the entire weight of said bucket being carried by said stem; a clapper sliding on said stem, said clapper seating in fluid tight relationship on 105 said seat; spring means for forcing said clapper against said seat; and flexible means for making a fluid tight joint between said clapper and said stem.

4. A bucket structure for use in deep well 110 pumps comprising a cylindrical bucket; a seat formed in said bucket about an opening extending therethrough; a bucket stem extending through said opening, the entire weight of said bucket being carried by said 115 stem; a clapper sliding on said stem, said clapper seating in fluid tight relationship on said seat; spring means for forcing said clapper against said seat; and flexible packing in said clapper about said stem.

In testimony whereof, I have hereunto set my hand at Los Angeles, California, this 17th day of September, 1918.

ARCHILLES A. BARTON.
